(57) **CLAIM**

The ornamental design for a chicken port feeder, as shown and described.

DESCRIPTION

FIG. 1 illustrates a front perspective view of a chicken port feeder;

FIG. 2 illustrates a bottom perspective view thereof;

FIG. 3 illustrates a front elevation view thereof;

FIG. 4 illustrates a rear elevation view thereof;

FIG. 5 illustrates a top plan view thereof;

FIG. 6 illustrates a bottom plan view thereof;

FIG. 7 illustrates a left-side elevation view thereof; and,

FIG. 8 illustrates a right-side elevation view thereof.
